US0D1080859S

(12) **United States Design Patent** (10) **Patent No.:** **US D1,080,859 S**
(45) **Date of Patent:** **** Jun. 24, 2025**

(54) **COMPRESSED ATOMIZER**

(71) Applicant: **Shenzhen Gong Tao Technology Co., LTD.**, Shenzhen (CN)

(72) Inventor: **Qingjun Jian, Ma Hao Kou** (CN)

(**) Term: **15 Years**

(21) Appl. No.: **29/805,451**

(22) Filed: **Aug. 26, 2021**

(51) LOC (15) Cl. **24-01**

(52) U.S. Cl.

USPC **D24/110**

(58) **Field of Classification Search**

USPC **D24/110, 107, 108, 164, 185, 186**
CPC **A61M 16/0063; A61M 16/021; A61M 16/10; A61M 16/1005; A61M 16/101; A61M 16/102; A61M 16/1025; A61M 16/1075; A61M 2205/3331; A61M 2205/3334; A61M 2205/3344**

(57) **CLAIM**

The ornamental design for a compressed atomizer, substantially as shown and described.

DESCRIPTION

FIG. 1 is a front elevation view of a compressed atomizer; FIG. 2 is a left side elevation view of a compressed atomizer; FIG. 3 is a right side elevation view of the compressed atomizer;

FIG. 4 is a back elevation of the compressed atomizer; FIG. 5 is a top plan view of the compressed atomizer; FIG. 6 is a bottom plan view of the compressed atomizer; and,

FIG. 7 is top, front, perspective view of the compressed atomizer.

The broken lines in the drawings depict portions of the compressed atomizer that form no part of the claimed design.

1 Claim, 7 Drawing Sheets
